UNITED STATES PATENT OFFICE

ARCHIE HUGH STRONG, OF FLUSHING, NEW YORK, ASSIGNOR TO MASTER DOMESTIC
REFRIGERATING COMPANY, INC., A CORPORATION OF NEW YORK

REFRIGERATING APPARATUS

Application filed March 20, 1928. Serial No. 263,113.

This invention relates generally to refrigerating apparatus and particularly to refrigerating apparatus of the absorption type.

An object of this invention is to provide a generally improved apparatus of the character mentioned, which is simple and inexpensive in construction, reliable in operation, durable and economical to maintain.

Further objects of the invention will become apparent from the following description, taken in connection with the accompanying drawings, in which Figure 1 is a diagrammatic view showing the several co-operative elements of the apparatus in their respective positions at the beginning of the heating period; Figure 2 is a view showing the evaporator partly in elevation and partly in section; Figure 3 is a transverse sectional view taken on the line 3—3 of Figure 1 and showing certain elements of the control mechanism in elevation; and Figure 4 is a vertical sectional view of a by-pass valve; and Figure 5 is a diagrammatic view of the control circuit for operating the gas and water valves, respectively.

The apparatus includes a generator 10, control mechanism 11, separator 12, condenser including a condenser coil 13, evaporator 14, and water trap 15.

The generator 10, comprises a container 17, adapted for the reception of a refrigerating medium, such as an aqueous, solution of ammonia to be heated and transformed into a gas, which is later condensed and thereafter transformed back into a gas to be absorbed by the liquid contents of the generator according to certain fundamental principles of refrigeration.

The container 17 is located within a suitable housing or casing 18 to which is connected a flue 19, adapted to carry products of combustion from the housing 18 caused by the gas burner 21, located within the housing 18 below the container 17. This gas burner 21 may be of any suitable construction and is adapted to be connected to a suitable source of fuel supply through a pipe 22 into which is tapped a pilot burner 23, arranged within the housing 10 and so located with respect to the burner 21 as to ignite the gas jets thereof

under certain conditions hereinafter more particularly described. Intermediate the gas burner 21 and the point of connection of the pilot burner 23 with the pipe 22, is located a valve 25 co-operatively connected with a solenoid 26, which, when energized, opens the valve 25 so that the burner 21 is supplied with gas from the pipe 22 to be ignited by the pilot 23.

Upon applying heat, through the instrumentality of the burner 21, to the generator 10, the ammonia is driven off from the aqueous solution within the container 17 through a pipe 27, connected at one end to the container 17 and at its other end to the separator 12. This separator 12 comprises an inner chamber 28 with which the pipe 27 communicates and from which a pipe 29 leads to the condenser 13. Around the chamber 28 is provided a water jacket 31, to the upper end of which is connected a waste water pipe 32, adapted to discharge the water from the jacket 31 as it flows therethrough from a water pipe 33 which passes through the condenser coil 13 and is connected to a suitable water supply, not shown, through a pipe 33 and a valve, to be hereafter described, and a pipe 34. The pipe 33 has an outside diameter somewhat less than the inside diameter of the condenser coil 13 so as to permit unobstructed passage of ammonia through the condenser, the condenser coil being connected at its opposite ends to the pipe 33 so as to form therewith a gas tight union.

From the construction of the separator 12, it will be understood that any water vapor passing into the separator 12 from the generator 10 will be condensed within the inner chamber 28, thus relieving the ammonia gas prior to its entrance into the condenser coil 13 of such water vapor as it may contain. As the water collects in the separator 12 it is returned by gravity through the pipe 27 to the generator 10.

During the heating period, a suitable valve 37, connected in a pipe line 38 leading from the pipe 34 through the generator 10 to the waste pipe 32 is maintained closed by a solenoid 39, which is connected in series with and energized simultaneously with the solenoid 100.

26. During such time as the solenoid 39 is energized and the valve 37 is maintained closed, water from the pipe 34 is permitted to pass through the pipe 33, condenser coil 13 and into the water jacket 31, from which it is discharged through the waste pipe 32. Inasmuch as the temperature of the water passing from the condenser coil 13 is somewhat raised in transforming the ammonia gas within the condenser into a liquid, the temperature of the inner chamber 28, of the separator 12 is maintained sufficiently high to prevent condensation of the ammonia within the separator but sufficiently low to effect condensation of water vapor that may pass from the generator 10 into the separator during the heating period and also, to pre-cool the ammonia gas before it reaches the condenser, so as to ensure efficient condensation 20 of the ammonia gas therein.

To one end of the condenser coil 13 is connected a chamber 40, which in turn is connected to a horizontally disposed ammonia receiver 41, constituting an element of the evaporator 14. Around the chamber 40 is located a brine tank 42, adapted for the reception of a quantity of brine, which, during the evaporation period, is chilled by the transformation of liquid ammonia into a gas as it passes from the evaporator 14 back through the condenser and into the generator 10, the chilled brine serving to maintain the chamber 40 at a fairly low temperature during the next succeeding generating period. By chilling the brine within the tank 42 during the evaporating period, such chilling may be utilized during the next succeeding generating period to reduce the liquefied ammonia to a relatively low temperature before it reaches the evaporator 14 (adapted to be located within a refrigerator box not shown) and thereby insuring against any appreciable rise in temperature within the refrigerator box during the heating period.

45. The evaporator 14 includes an evaporating unit in the form of a pipe 44 which is so shaped as to provide a plurality of U-shaped portions. Opposite ends of the pipe projecting into the receiver 41, one end being at a slight distance above the other (see Fig. 2) so as to ensure filling of the pipe with liquid ammonia as it is received by the receiver 41 from the condenser 13. This evaporator unit is housed within a brine receptacle 45 adapted 50 for the reception of a quantity of brine, which, during the evaporating period is substantially cooled so as to maintain the refrigerator box, not shown, at a low temperature during the next succeeding heating period following a period of evaporation.

If for any reason the separator 12 should fail to condense any part of the water vapor present in the ammonia gas as it passes from the generator, and such water vapor becomes

later condensed and finds its way into the evaporator 14, such water will remain in the lowermost portion of the evaporator unit 44 after the evaporating period has been completed, and will be automatically removed 70 from the evaporator unit 44 during the next heating period, and collected in the water trap 15. This water trap 15 comprises a vertically disposed receptacle 46 having its upper end connected by a pipe 47 to the lower portion of the evaporator unit 44, as shown most clearly in Figure 2 the lower end of the receptacle 46 being connected to the generator 10 through a pipe 48 and a normally closed hand operated valve 49. This automatic removal of water from the evaporator unit 44 will be effected as follows:

During the evaporation period, the pressure within the water trap 15 is lowered simultaneously with the lowering of the pressure in the evaporator unit 44 and the remainder of the system. However, when the heating period begins, pressure from the generator 10 is transmitted through the separator 12, condenser 13, and receiver 41 to the evaporator unit 44, with the result that any water remaining in the evaporator unit, upon the completion of the evaporating period, is forced up through the pipe 47 and into the water trap 15 as the pressure in such trap rises correspondingly to the pressure in the remaining part of the system. In order to drain the water trap 15 of such water as may be trapped therein, from time to time it is only necessary, at long intervals, to open the valve 49 and allow the water to return to the generator 10, the appropriate time for opening such valve being during the evaporating period. In the event any unevaporated ammonia remains in the evaporator unit 44, 105 upon completion of the evaporating period, such ammonia is prevented from accumulating as a liquid in the water trap 15 due to the fact that this trap is located in proximity to and derives a sufficient amount of heat 110 from the flue 19 to evaporate any such ammonia during the heating period. It is to be particularly noted, that it is essential to such evaporation that said water trap 15 shall remain in continually open communication 115 with the evaporator through said pipe 47.

The control mechanism shown is substantially the same as that shown, described and claimed in my Patent No. 1,646,712, issued October 25, 1927, although modified in its 120 adaptation to the new apparatus shown, described and claimed herein. This control mechanism 11 operates to open the gas valve 25 and simultaneously to close the water valve 37, and comprises a frame 51 in which 125 is journalled a shaft 52, carrying rigidly thereon a toothed segment 53. Upon the shaft 52 is journalled an arm 54 to which is pivotally connected a pawl 55 provided at its free end with a pin 56, one end of the pin 130

being provided with a roller 57 (see Figure 3) and the other end of the pin being connected to the shaft 52 by a tension spring 58. The arm 54 is connected by a link 59 to a lever 60 which in turn is pivoted to a suitable support or housing 61, with which a compression spring 62 is associated. This compression spring is adapted to engage a lever 63, which is pivotally connected at one end to the housing 61 and linked at its other end to the lever 60 by a link 64. The arm 54 is moved downwardly from its uppermost position shown in Fig. 1, by the spring 62, and is moved upwardly to its position shown in Fig. 1 through the instrumentality of a sylphon bellows 66, which, by means of a tube 67, is connected to a suitable thermostat 68 associated with the ammonia receiver 41.

To the toothed segment 53, is suitably connected a strip of insulating material 39 which carries a U-shaped metallic contact member 70, having a pair of resilient contact fingers 71, provided at their respective free ends with contacts 72. The contacts 72 are adapted to engage fixed contacts 73 carried by and suitably insulated from the frame 51, with the result that a circuit is closed, from a suitable source of electrical energy E, through the conductor 75, metallic contact member 70 and the conductor 76, which connects the solenoids 26 and 39 in the series. When the circuit, including the solenoids 26 and 39 is closed, the gas burner valve 25 is opened and the valve 37 controlling the supply of cooling water to the apparatus is closed. The control mechanism 11 also includes a release arm 79 which is pivoted at its lower end to a suitable support and is connected at its upper end to a link 80, the link being pivotally connected to an arm 81 pivotally supported, as at 82, upon the housing of a sylphon bellows 83. This sylphon bellows is connected with the container 17 through a pipe 84, and is adapted to move the arm 81 against the influence of a tension spring 85, as the temperature in the container 17 is increased during the heating period. Such movement of the release arm will effect the release of the pawl 55 from the toothed segment 53, thereby allowing such segment to drop by gravity with the result that the circuit through the solenoids 26 and 39 is opened.

During the heating period, a sylphon bellows 87, which is connected through a pipe 88 to a bulb containing a thermostatic fluid and extending within the combustion chamber in the housing 18 surrounding the receptacle 17, is distended axially by expansion of said fluid to open a valve 89 carried within a housing 90, with the result that water during the heating period, at which time the valve 37 is closed, is permitted to flow from the pipe 34 through the compartments A and B of the valve housing 90 and into the pipe 33

which conveys the water through the condenser 13, from which it is discharged into the separator 12 to be carried therefrom by the waste pipe 32. After the heating period has begun and prior to such time as the valve 89 is opened, a small quantity of water passing through the apertured diaphragm 91 disposed in the pipe 38 intermediate the valve 37 and the water supply pipe 34, is permitted to pass into the pipe 33 through a pipe 92 without passing through the valve housing 90, the pipe 92 being connected to the pipe 33 outside of the valve housing 90 at the discharge side thereof and being coupled to the pipe line 38 intermediate the valve 37 and the aperture 30 diaphragm 91. The valve 89 performs the highly important function of reducing to a minimum the amount of water required for efficient operation, inasmuch as such valve is open only during the relatively short heating period, which may be as short as approximately forty minutes out of twenty-four hours, and thereafter only during a relatively shorter length of time at the beginning of the absorption period. During that portion of the absorption period while the valve 89 is open, a small amount of water passes through the aperture of the diaphragm 91 and the valve 37, whereas the remaining supply of water to the pipe 38 is supplied from the supply pipe 34 through the valve housing 90 and pipe 92. That is to say; when the valve 37 opens by the action of the solenoid 39, said valve 89 does not immediately close, because its closure can be effected only by the contraction of said sylphon 87, and such contraction is effected, comparatively slowly, in accordance with the lowering of the temperature in the combustion chamber surrounding said container 17 within said casing 105 18. Consequently, at the beginning of the time during which the valve 37 is open, said valve 89 is also open, so that the supply of water thru said valve 87, by way of the apertured diaphragm 91, is temporarily augmented 110 by the downward flow of water thru said pipe 92. Such flow thru the pipe 92 is, of course, diminished to nothing as said valve 89 gradually closes as a consequence of the loss of heat from said combustion chamber and, 115 thus, said valve 89 may be termed automatically actuated thermally controlled means for varying the supply of cooling medium to the generator during the absorption period. At or about the time the contents of the generator 10 become cooled to a substantial degree by the water directed into the pipe 38 through the aperture of the diaphragm 91 and the valve housing 90, the temperature 120 within the housing 18 is so reduced as to permit the sylphon bellows 87 to so act, in co-operation with the compression spring 93 associated therewith, as to close the valve 89, thereby cutting off the main supply of water 125 from the supply pipe 34 to the pipe 38. How- 130

ever, with the valve 89 closed, a small amount of water is permitted to pass through the aperture of the diaphragm 91 and the valve 37 into the pipe 38. Although the amount of water which is permitted to pass through the aperture of the diaphragm 91, while the valve 89 is closed and the valve 37 is opened, is comparatively small, it is ample to maintain the contents of the generator at a sufficiently low temperature to enable the absorption period to be efficiently carried out.

In describing the operation of the apparatus, it will be assumed that the absorption period has been completed and that the electric circuit through the conductors 75 and 76 has been closed by bringing the contacts 72 into engagement with the contacts 73, the engagement between such contacts having been made by reason of a rise in temperature within the ammonia receptacle 41 which caused the sylphon bellows 66 to so act upon the lever 60 as to move the arm 54 and toothed segment 53 to their respective positions shown in Fig. 1, the toothed segment 53 and arm 54 moving together under such conditions, due to the engagement of the pawl 55 with the toothed segment 53. Upon the closing of the electric circuit through the solenoids 26 and 39, the valve 25 is opened and the valve 37 is closed. By opening the valve 25, gas is supplied to the burner 21 and ignited by the pilot 23, and by closing the valve 37, water from the supply pipe 34 is cut off from the pipe 38 which passes through the generator 10 and serves to cool the contents thereof. Upon the application of heat to the generator 10, the ammonia carried therein is driven off as a gas through the pipe 27 and directed into the inner chamber 28 of the separator 12. Almost simultaneously with the application of heat to the generator from the burner 21, air within the housing 18 is heated to a sufficient degree to cause the sylphon bellows 87 to open the valve 89. During the short time between the application of heat to the generator from the burner 21 and the time the valve 89 is opened, a small amount of water passing through the aperture of the diaphragm 91 is supplied through the pipe 92 to the pipe 33 and condenser 13, but as soon as the valve 89 is opened, the main supply of water from the pipe 34 is permitted to pass through the valve housing 90 and into the pipe 33 to be thereafter directed through the condenser 13. The water passing from the condenser 13 is directed through the pipe 33 into the jacket 31 of the separator 12, from which it is permitted to pass through the pipe 32 and on to waste. Inasmuch as the jacket 31 of the separator 12 is supplied with water, any water vapor passing with the ammonia into the inner receptacle 28 is condensed therein and allowed to pass back into the receptacle 17 by gravity. The cooling effect of the water within the

jacket 31 is insufficient, however, to condense the ammonia, with the result that the ammonia passes from the separator through the pipe 29 and into the condenser 13. It is in the condenser 13 that the ammonia is condensed by the water passing through the pipe 33, which pipe passes through the condenser coil 13 and emerges therefrom at the other end thereof. As the ammonia gas is condensed in the condenser 13, the resultant liquid flows by gravity into the chamber 40 where it is pre-cooled by the cold brine within the tank 42. This pre-cooled ammonia passes from the chamber 40 by gravity into the ammonia receiver 41 and into the evaporator unit 44. As the liquefied ammonia enters the ammonia receiver 41, during the heating period, pressure within the entire system is increased, with the result that any unevaporated liquid such as water remaining in the bottom of the evaporator unit 44 upon completion of the previous evaporating period, is forced over through the pipe 47 into the water trap 15. As the heating period continues, the evaporator unit 44 becomes filled with liquefied ammonia and the surplus or excess liquefied ammonia collects within the ammonia receiver 41. Upon the completion of the heating period, which is determined by the rise in temperature within the generator 10, the sylphon bellows 83 is so acted upon as to swing the trip arm 79 to the right, whereby the pawl 55 is released from the toothed segment 53, thus permitting such segment together with the contact member 70 to swing by gravity to the right as viewed in Fig. 1. Such movement of the contact member, opens the circuit through the conductors 75 and 76 with the result that the valve 25 is closed, thereby the flame from the burner 21 is extinguished, and the valve 37 is opened, whereby the pipe 38 is placed in communication with the supply pipe 34 through the aperture of the diaphragm 91 as well as through the valve housing 90. The valve 89 within the housing 90, remains open for a short time after the valve 37 is opened, with the result that water from the supply pipe 34 is permitted to pass through the valve housing 90 and the pipe 92 into the pipe line 38, thus furnishing a sufficient amount of water to the pipe 38 to effect relatively rapid cooling of the contents of the generator 10. As the interior of the housing 18 drops in temperature the valve 89 is permitted to close under the influence of the sylphon bellows 87 and its associated spring 93, with the result that only a relatively small amount of water is furnished to the pipe 38 through the aperture of the diaphragm 91. As the contents of the generator 10 are cooled, pressure in the system drops, and the liquefied ammonia within the evaporator 14 is transformed by evaporation from a liquid into a gas which is permitted to pass back through the condenser 13

13 and separator 12 and into the generator, where it is absorbed by the liquid remaining therein. Such evaporation serves to lower the temperature of the brine within the brine receptacle 45 and thus reduce the temperature of the refrigerator box, not shown, with which the evaporator is adapted for use. During evaporation the temperature of the brine contents of the tank 42 is also lowered, 10 the low temperature of the brine therein being utilized during the next generating period to pre-cool the liquefied ammonia prior to its entrance into the evaporator 14. Inasmuch as the volume of brine within the receptacle 45 is relatively large and serves as a reservoir of cold, and since the liquefied ammonia is pre-cooled before it enters the receiver 41, it is possible to maintain the brine contents of the receptacle 45 and hence the 15 contents of the refrigerator box at a relatively low temperature even during the generating or heating period. During the evaporating period, the expansible medium within the pipe 67 is so reduced in volume, as to 20 permit the spring 66 to return the lever 60, with its associated arm 54, to its lowered position, thus placing the pawl 55 in a proper position with respect to the toothed segment 53 to enable such segment to be lifted to its 25 position shown in Fig. 1 as the arm 54 is swung to its position shown in that figure. At or about the time the evaporating period is completed the temperature of the ammonia receptacle 41 will have risen a sufficient degree to expand the medium within the pipe 67, with the result that the sylphon bellows 66, acting against the influence of the spring 62, swings the arm 60 upwardly. Inasmuch as the arm 60 is connected to the arm 54 and 30 the latter arm is interlocked with the toothed segment 63, the contacts 72 are moved into engagement with the fixed contacts 73 upon a sufficient rise in temperature within the ammonia receiver 41. By reason of the engagement thus effected between the contacts 72 and 73, the circuit through the solenoids 26 and 39 is again completed whereupon the heating period is resumed and the succeeding stages in the cycle of operation are again 35 carried out as above described.

While the invention is herein shown and described, as being embodied in one form of apparatus, it will be understood that various changes may be made without departing from the spirit of the invention or the scope of the following claims.

What is claimed is:

1. In a refrigerating apparatus, a generator for a refrigerant, periodically operated means for heating the contents of the generator, a condenser for condensing the evaporated refrigerant, an evaporator, a separator located intermediate of and communicating with the generator and the evaporator for freeing the evaporated refrigerant 40
2. In a refrigerating apparatus, a generator for a refrigerant, periodically operated means for heating the contents of the generator, a condenser for condensing the evaporated refrigerant, an evaporator, a separator located intermediate of and communicating with the generator and the evaporator for trapping during a given generating period such water as may have remained in the evaporator upon completion of the last preceding evaporating period, the water trap comprising a receptacle adapted for communicating at its lower end with the generator and being in communication at its upper end with the bottom of the evaporator and depending for its operation upon rise in pressure within the evaporator during the generating period; 45

the means connecting said water trap with the evaporator continually affording unrestricted communication, and thus continually permitting any ammonia in said trap to be vaporized and returned to the evaporator; a conduit extending from said trap to the generator; and a valve in said conduit below said trap; whereby communication of said trap with said generator is normally prevented, but may be established, at the will of the operator, to drain the trapped water into the generator.

4. In a refrigerating apparatus, a generator for a refrigerant, periodically operated means for heating the contents of the generator, a condenser for condensing the evaporated refrigerant, an evaporator, a pre-cooling device including a container for the refrigerant and a container for brine in operative relation therewith, adapted to utilize the refrigerant as it passes from the evaporator to the generator during the evaporating period to establish a source of cold to be utilized during the generating period to pre-cool the condensed refrigerant as it passes from the condenser into the evaporator.

5. In a refrigerating apparatus, a generator for a refrigerant, periodically operated means for heating the contents of the generator, a condenser for condensing the evaporated refrigerant, an evaporator, a chamber located intermediate of and communicating with the condenser and the evaporator, a tank surrounding the chamber and adapted for the reception of brine to be cooled by the refrigerant as it passes from the evaporator into the generator during the evaporating period, the brine thus chilled being utilized upon the next succeeding generating period to pre-cool the refrigerant prior to its entrance into the evaporator.

In testimony whereof, I have affixed my signature to this specification.

45 ARCHIE HUGH STRONG.
